UNITED STATES PATENT OFFICE

CHARLES H. HISER, OF SPRINGFIELD, OHIO, ASSIGNOR TO THE SPRINGFIELD METALLIC CASKET COMPANY, OF SPRINGFIELD, OHIO, A CORPORATION

HINGE

Application November 14, 1927. Serial No. 233,122.

This invention relates to hinges, it more particularly relating to a combined hinge for the inner and outer tops of metallic caskets.

The object of this invention is to provide a combined hinge for two hinged members of a character which will permit either one of the members to be removed without the necessity of the removal of screws, pintles, or other fastening devices.

10 A further object of the invention is to provide a hinge which will be simple in construction, economical in manufacture and effective for the purpose for which it is designed.

In the accompanying drawings:

15 Fig. 1 is a plan view of a portion of a metallic casket showing one of my improved hinging devices applied thereto.

Fig. 2 is a section on the line *a—a* of Fig. 1.

Fig. 3 is a view of the inner end of the 20 hinge.

Fig. 4 is a section on the line *b—b* of Fig. 2.

Referring to the drawings, 1 represents the body of a metallic casket, the upper edges of which are bent to shape to provide a horizontal supporting ledge 2 in the usual manner. A portion of the outer top is shown at 4 and a portion of the inner top at 5. The lower edge of the outer top is bent to provide a lower horizontal flange 6 having its inner 25 edge bent at right angles as indicated at 7 to furnish a finish to receive a wooden strip (not shown) to which the upholstering is attached and the lower edge of the inner top is shaped to provide a hollow ledge 8 having a suitable filler 9, the ledge resting upon a gasket 10 located in a groove 11 formed in the ledge 2. Suitable means, not shown in the present case, are employed for clamping the inner top to position so as to form an air 30 tight joint.

My improved hinge is constructed as follows: There is shown at 12 a metallic plate which is fastened by screws 13 to the upper surface of the body ledge 2. These screws 35 pass through apertures in the ledge 2 and are screwed into a strap 14 which extends the full length of the ledge and is secured thereto by spot welding or in any other suitable way. The outer portion of the metallic plate 12 is preferably reduced in width

and has its end upturned to form a tongue as indicated at 15. The intermediate portion of this tongue is formed on a reverse curve as shown in Fig. 2 so that the outer portion of the tongue is offset from the inner portion thereof, and the metal at the juncture between the plate 12 and the tongue 15 is bent to form a rounded channel 16.

The inner end of the plate 12 is upturned as indicated at 17 and the free end of the upturned portion 17 is reduced to form a tongue 18. The tongue 15 forms a hinge for the outer lid and the tongue 18 forms a hinge for the inner lid.

Secured to the ledge 8 of the inner lid by screws 19 is a plate 20, the outer side thereof being upturned as indicated at 21 with its free edge bent laterally as indicated at 22. The portions 21 and 22 at their juncture are cut away so as to form an opening 23 slightly larger than the width of the tongue 18, a part of this opening being located in the vertical portion 21 and a part in the horizontal portion 22. To place the inner lid upon the hinge, the lid is merely held in horizontal position and the apertured portion of the plate 20 threaded upon the tongue 18.

As afore stated, the outer lid 4 is hinged on the tongue 15 and to that end the lower horizontal flange of the outer lid is bent to form a pocket 24 and at the outer end of the pocket the plate is punched to form a slotted opening 25 to receive the tongue 15. When the outer lid 4 is raised, the inner wall of this opening 25 rides in the recessed portion 16 which forms a bearing therefor. When it is desired to remove the outer lid 4, it must be raised to an incline of 45 degrees to permit the walls of the opening 25 to clear the intermediate curved portion of the tongue 15.

By this arrangement it will be seen that a very simple, economical and effective hinge is provided for both the inner and outer lids of a character which will permit the ready removal and replacement of the lids. While but one hinge has been shown and described, it will be understood that as many of the hinges will be employed as may be required.

Having thus described my invention, I claim:

1. In a container having an outer lid and an inner lid, a plate secured to the upper edge of said container having its inner end bent upwardly and reduced to form an inner tongue, a hinge member secured to the inner lid having an angular portion provided with an aperture at the angle thereof to receive said inner tongue, said plate having its outer edge provided with an outer tongue adapted to be received in an apertured portion of the outer lid.
2. In a container having an outer lid and an inner lid, a horizontal plate secured to the upper edge of the container having its outer edge upturned to form a tongue with the juncture between the plate and tongue forming a rounded channel, adapted to be received in an aperture in the outer lid, a tongue formed on the inner edge of said plate, and an apertured member on the inner lid to receive said inner tongue.
3. In a container having an outer lid and an inner lid, a horizontal plate secured to the upper edge of said container having its inner edge upturned to form a tongue adapted to be received in an apertured portion of the inner lid and having its outer edge provided with an outer tongue adapted to be received in an apertured portion of the outer lid.

In testimony whereof, I have hereunto set my hand this 25th day of October, 1927.

CHARLES H. HISER.
